UNITED STATES PATENT OFFICE.

VAN ORAN JEFFRIES, OF COLUMBUS, OHIO.

CONCRETE BUILDING STRUCTURE.

Application filed May 16, 1922. Serial No. 561,441.

To all whom it may concern:

Be it known that VAN ORAN JEFFRIES, a citizen of the United States, residing at Columbus, in the county of Franklin and 5 State of Ohio, has invented certain new and useful Improvements in Concrete Building Structures, of which the following is a specification.

The present invention is directed to improvements in concrete building structures, and has for its primary object to provide a wall so constructed as to produce a hollow chamber, which serves as an air space for excluding dampness. 10
15 A further object of the invention is to provide a wall structure of this nature so formed that portions of the supporting posts will project inwardly beyond the plane of the inner surface of the wall so as to permit the application of laths, the outer faces of the posts being completely imbedded in the wall.

A still further object of the invention is to provide novel means, in the form of a 20 wire truss, to retain the posts in their proper position during the time the wall is being poured.

Still another object of the invention is to provide a novel form of mold to be used 30 in producing a wall wherein an air space is provided by the plaster and laths, and the inner face of the cement wall, whereby an air space is produced.

With these and other objects in view, as 35 will appear as the description proceeds, the invention consists in the novel features of construction, combination of elements and arrangements of parts, and hereinafter to be fully described and pointed out in the 40 appended claims.

In the accompanying drawing:

Figure 1 is a longitudinal sectional view showing the manner in which the mold is arranged previous to pouring the cement.

Figure 2 is a horizontal sectional view through a corner of the wall, showing the relative arrangement of the corner posts, and after the wall has been poured.

Figure 3 is a sectional view on line 3—3 50 of Figure 1.

Figure 4 is a vertical sectional view taken through a section of the wall showing means to permit free circulation of air in the air space.

Figure 5 is a horizontal sectional view 55 through a section of the wall, showing a slightly modified form of the invention.

Referring to the drawing, and particularly to Figure 1 thereof, there is shown a pair of vertically arranged posts 1, which 60 may be supported in any well known manner upon a suitable foundation (not shown), said posts being provided at suitable points with spaced transverse bores 2, the purpose of which will appear later.

Fixed to the opposite sides of the posts 1 are dovetailed vertically disposed strips 3, said strips being arranged between the bores 2. The wire tie 4 consists of two strands 5 of suitable gage wire, portions of which are 70 engaged in the bores 2. It is obvious that upon placing a bar or any suitable tool between the strands 5, and rotating the same that the strands will be twisted into mutual engagement, thus connecting the posts 1 75 in a rigid manner. It will be noted that the strands 5 have portions of their length engaged with the strips 3, consequently holding said strips in proper position relative to the posts 1.

After the posts 1 have been properly positioned, the mold 6 is applied, this mold consisting of boards 7, which are of such length as to fit snugly between a pair of the posts 1, and with the outer faces in a 85 plane with the inner faces of the posts. To prevent the boards 7 from moving inwardly between the posts 1 vertical cleats 8 are provided for engaging the inner faces of the 90 posts 1, as clearly shown in Figure 1 of the drawing.

The mold 6 consists of side boards 9 which are secured to the posts 1 by nails 10, and it will be noted that the boards 9 are so nailed as to be spaced from the adjacent faces of 95 the posts 1, the purpose of which will appear later.

In Figure 2 of the drawing the posts 1 are arranged for forming a support for the corners of a building wall, the only difference in this structure over that shown in Figure 1 is that the strips 3 are eliminated upon one side of the posts, and it will be noted that the manner of attaching the tie 4 is substantially the same.

Assuming that cement has been poured into the mold it will be obvious that it will settle as shown in a portion of Figure 1

of the drawing, and since the nails 10 support the boards 9 in spaced relation with the posts 1, it is obvious that when these boards are removed that the cement will remain as shown, and it will be noted that the tie 4, strips 3 and the major portion of the posts 1 are imbedded in the cement. Upon removing the boards 7 the inner end of the posts 1 will project beyond the wall 10 face, a distance corresponding to the thickness of said boards. This is illustrated clearly in Figure 2, of the drawing wherein the posts 1 have their inner ends projected inwardly of the inner face of the wall 11, whereupon the laths 12 can be nailed or otherwise secured to the inner faces of the posts 1, thereby producing an air chamber 13. It will be of course understood that the nails 10 used for supporting the boards 9 will be removed with the boards.

In Figure 4 of the drawing the wall is shown with air inlets 14, which are tapered and inclined downwardly and outwardly, the inner ends of said openings communicating with the air chambers 13 so as to permit a free circulation of air in said chambers. By inclining the openings 14, as shown, it is obvious that rain water cannot flow upwardly therein and into air space 13.

In Figure 5 of the drawing there is shown a slightly modified form of the invention, this form being designed to eliminate a number of the posts 1, so that a wall can be built at a smaller cost, and in this instance uprights 15 are employed and are placed against the inner face of the wall 11 after which the wire loop 16, engaged there-around, said loop being connected with the central portion of the tie 4. This loop 16 is twisted into engagement with the strands 5 of the tie 4 which remain spaced after the tie wires have been twisted to firmly hold the posts 1 in place, and since the tie 4 is imbedded in the wall 11 and the loop 16 partially imbedded therein, it will be apparent that the loops will be firmly secured so as to hold the uprights 15 in tight engagement with the inner face of the wall 11. These uprights are of the same width as to have

their inner faces in a plane with the inner faces of the posts 1, after which the laths 12 are secured to the respective posts and uprights.

It will be noted that in Figure 4 the floor 17 is separated from the air chamber 13 by a section of cement 18, therefore should a fire start upon one floor of a building the flames will be prevented from passing from one floor to another through the air chamber 13.

The posts 1, as well as the uprights 15 are treated with any suitable water proofing material which will prolong the lives of these parts. This is deemed essential since the cement poured is in a moist state, and consequently by coating these parts with water proofing material the life thereof will be prolonged indefinitely.

What I claim is:

1. In a structure of the class described, a cement wall, a plurality of vertically extending posts imbedded in the wall, said posts having spaced bores formed therethrough, horizontally extending wire strands passing through said bores, and twisted about each other between the posts.

2. In a structure of the class described, a cement wall having a continuous outer surface, a plurality of posts embedded in the wall, said posts having strips interlocked with the wall, the inner faces of said posts extending beyond the inner surface of the wall, and wire strands passing through the posts and having portions thereof engaged with the strips, said strands being twisted together intermediate the posts.

3. In a structure of the class described, a cement wall, a plurality of posts imbedded in the wall, strips engaged with the sides of the posts, a pair of wire strands, portions of said strands passing through the posts, and engageable with the strips to hold the same in mutual contact with the posts, said strands being twisted together intermediate the posts.

In testimony whereof I affix my signature.

VAN ORAN JEFFRIES.
